Primary Examiner — Rhea Shields

(57) **CLAIM**

The ornamental design for a massage head of the fascia gun, as shown and described.

DESCRIPTION

The patent or application file contains at least one drawing executed in color. Copies of this patent or patent application publication with color drawing(s) will be provided by the Office upon request and payment of the necessary fee.

1. Massage head of the fascia gun

1.1 : Front

1.2 : Back

1.3 : Left

1.4 : Right

1.5 : Top

1.6 : Bottom

1.7 : Perspective

The usage of this massage head of the fascia gun is being fixed on the fascia gun to massage different parts and skin of people; The main point of the design is the shape and pattern of the massage head of the fascia gun to make massage more effective; The best view to show the design point is the perspective view.
